CLAIM

The ornamental design for a bluetooth speaker, as shown and described.

DESCRIPTION

FIG. 1 is a rear elevational view of a bluetooth speaker showing my new design;

FIG. 2 is a front elevational view thereof;

FIG. 3 is a top plan view thereof;

FIG. 4 is a bottom plan view thereof;

FIG. 5 is a right side view thereof;

FIG. 6 is a left side view thereof; and,

FIG. 7 is a perspective view thereof.

The broken lines shown are included for the purpose of illustrating portions of the bluetooth speaker that form no part of the claim.
